UNITED STATES PATENT OFFICE.

EDWARD ODON BENJAMIN, OF NEWARK, NEW JERSEY, ASSIGNOR TO INTERNATIONAL OXYGEN COMPANY, A CORPORATION OF NEW JERSEY.

EVAPORATING AND CONDENSING APPARATUS.

Application filed July 18, 1919. Serial No. 311,692.

To all whom it may concern:

Be it known that I, EDWARD O. BENJAMIN, a citizen of the United States, and resident of Newark, in the county of Essex and State 5 of New Jersey, have invented certain new and useful Improvements in Evaporating and Condensing Apparatus, of which the following is a specification.

My present invention relates to a complete unitary system for distilling liquids and it includes certain important improvements in the evaporator and also in the condenser as well as in the system as a whole.

An important feature of the system consists in making the evaporators in standard units and the condensers in standard units so that condensers may be added to or taken from the system, preferably at the outlet end thereof, to take care of the condensation under special conditions, as where a liquid absorbing great or less latent heat is being evaporated, or where the cooling water available is warmer or colder than usual; also additional evaporator units may be added to or taken from the evaporating end of the system to multiply or reduce the total output. The condensers are preferably arranged in parallel between a single vapor supply conduit and a single discharge conduit and the evaporators, if more than one is used, are preferably also in parallel relation between a liquid supply conduit and a vapor delivery conduit. The cooling medium preferably circulates through the condensers in series preferably beginning with the one nearest the outlet of the delivery conduit, and where water is being distilled and water is also used as a cooling medium, part of the water warmed by circulating through the condensers may be utilized to keep up the supply in the evaporators.

Thus, while the evaporating and condensing units each have special structural advantages and may be coupled up in any desired way, the preferred system embodies three main conduits, namely, an upper steam or vapor conduit, a lower conduit for the discharge of the condensed liquid, a plurality of condenser elements connected in parallel relation across said conduits, and a third conduit through which the cooling medium traverses the condensers in series; also where more than one evaporator is used, the added evaporator preferably discharges through 55 the other into said steam or vapor conduit.

In the preferred construction each unit carries its own section of each of the main conduits so that extensions of the system may be effected merely by bolting together the conduit sections of the similar units.

In the preferred arrangement, there is preferably also an intermediate section between the cooling conduit and the intake conduit of the evaporators, whereby all excess of the water or other cooling medium, 60 beyond what is necessary to replenish evaporation, is permitted to overflow and escape. This overflow water may be run through ordinary cooling coils and returned to the intake end of the cooling water conduit of 70 the condensers or, where water is cheap, the excess may be permitted to run to waste.

Preferably, also, there is a special unit for discharge of the condensed liquid. This unit preferably embodies a trap to maintain 75 a certain amount of condensed liquid in the discharge conduit so that the condensed liquid from the condenser nearest the cooling water intake and therefore coolest, may mingle with and lower the temperature of 80 the warmer condensed liquid from condensers nearer the cooling water outlet where the cooling water is warmest. In this way the temperature of the condensed liquid discharged from all the condensers is averaged 85 and they overflow at a fairly uniform temperature. Moreover, in the extreme case where the hottest of the condensers might otherwise discharge steam which would have to be vented through the discharge pipe, 90 the above described arrangement will compel the steam to pass through the cooler liquid adjacent the outlet, which will condense it. While this provision will take care of practically all operating conditions, I 95 preferably provide a steam vent in the top of the trap to take care of special emergencies as for instance, entire failure of the supply of cooling medium, or sudden evolution of steam such as sometimes occurs 100 with some liquids or under special conditions. This vent will also prevent the possibility of siphoning the liquid in either direction.

The outlet trap makes it possible to impose a pressure slightly above atmosphere throughout the entire distilling system, said pressure being limited to the hydrostatic head existing when the water level in the condenser outlets has been depressed to the 110

blow-off point. Similarly, the possible vacuum is limited by the decrease of head existing when the level in the trap has been depressed enough for air to be sucked in.

These pressures must be taken account of in determining the height of the overflow stand-pipe in the above mentioned overflow unit, since the level of the water in the evaporators can fluctuate below or above the level of the overflow a limited distance equal to these differences between trap up-take and condenser outlets.

The stand-pipe in the overflow unit will preferably have its height adjusted with reference to the outlet trap so as to maintain a desired level of the liquid in the evaporator and incidentally to vary such level to suit the particular liquid to be evaporated. Liquids having a high surface tension giving rise to considerable foaming and frothing during boiling, should have a much lower level in the evaporator than liquids which boil without foam. The desired change of level may be accomplished by screwing the overflow pipe up or down or by substituting a longer or shorter length of pipe. Where the liquid is one which does not foam, the maximum efficiency of the evaporator may be obtained by raising the liquid level as high as is possible without incurring danger of having unevaporated particles projected into the vapor outlet conduit.

Where the liquid being evaporated is not the same as that used for cooling, the stand-pipe supply unit may be connected to a source other than the outlet of the cooling medium.

The evaporator units are preferably ribbed or otherwise so constructed as to expose a relatively large surface to the source of heat. Where burners are used, they are preferably so constructed as to have gas outlet holes venting horizontally, preferably under and protected by an overhanging bead or ledge. This prevents any accumulation of soot or dust from falling back upon the jets. When steam is used as the means of heating the evaporator, the burners may be omitted and the lower part of the evaporator jacketed. Where distilled water is to be produced from steam, my evaporator units may be dispensed with and any desired form of boiler or steam generator may be connected directly to the condenser system.

In order to prevent back drip of condensed material into the evaporator, which would involve continuous reevaporating, a semi-tubular trough is formed around the interior walls near the top of the evaporator. The top of the latter is slightly arched or domed so that any accumulation of condensed drops of liquid will flow toward the side walls and be caught in the trough from

which they will flow into the vapor conduit and thence through the condensers.

The active condensing element of the condenser units consists essentially of a thin walled, cellular, metallic structure which may be substantially similar to the well-known structures now commonly employed for automobile radiators, the types affording a zig-zag or tortuous path for the vapor being particularly desirable. Such cellular units are utilized in such a way that the steam or vapor to be condensed flows down through the interior thereof in much the same way that the hot water flows down through an automobile radiator, while the cooling medium traverses the cellular unit horizontally, in a relation corresponding to the air draft through the automobile radiator.

Where the cooling medium is liquid, the volume required is much less than where air or gas is used for cooling; hence the horizontal passages through the condensers may be cross-sectionally elongated and narrowed to give greater cooling surface and less cross-sectional area for the cooling passages. The tortuous character of the vapor passages in the condensing element and the free drainage which they afford for the condensed liquid, prevent the well-known water hammer effects and vibrations, which might otherwise result from the production of vacuum through rapid or sudden condensation.

Each cellular condensing element is removably mounted in its casing and said casing affords a container and conduit for the cooling medium, to, through and from the condensing element as well as a main conduit section for the steam or vapor and a main conduit section for the condensed liquid. Both of these main conduits are of ample cross section so as to have a certain storage or reservoir capacity adapted to somewhat steady the supply and discharge respectively. The cooling conduit connections are also of ample capacity, preferably predetermined with respect to the total flow capacity of the horizontal cooling passages through the condensing radiator element. In this way a slight pressure drop may be localized between the supply side and the discharge side of each radiator element. This has a tendency to cause a substantially equal flow of the cooling medium through all of the radiator passages. Entering the cooling water at the bottom and discharging at the top of the casing of each condenser unit, so that the coolest and therefore heaviest water is at the bottom, and naturally flows upward as it becomes warmer and lighter, tends to make the flow more uniform, and to create a situation where the hotter water on the outlet side of the radiator element will rise toward the outlet with

greater rapidity the hotter it gets, and so will tend to draw cool water through from the inlet side, at points where it is most needed to keep down the temperature.

5 The above and other features of my invention may be more fully understood from the following detailed description in connection with the accompanying drawings, in which—

10 Figure 1 is a vertical, longitudinal, central section showing the preferred arrangement of the combined evaporating and condensing system;

15 Figure 2 is a face view of one of the condensing units;

Figure 3 is a section on the line 3—3, Figure 2;

Figure 4 is a section on the line 4—4, Figure 2;

20 Figure 5 is a vertical central section on the line 5—5, Figure 3;

Figure 6 is an exterior side elevation of an evaporator unit with part of the heat jacket broken away to show the construction;

25 Figure 7 is a section on the line 7—7, Figure 6; and

Figure 8 is a cross sectional detail on the line 8—8, Figure 1.

In these drawings, the system, as distinct 30 from the units, comprises one or more evaporators A; steam or vapor conduit B; liquid discharge conduit C, terminating in trap outlet D; condensing radiator elements E arranged in parallel across said conduits B and C; cooling medium conduit F terminating in overflow conduit G; and evaporator supply conduit H.

An evaporator unit suitable for the system is shown in Figures 1, 6 and 7. It 40 preferably consists of a lower section 1, and an upper section 2 each consisting of an integral casting, the sections being secured together by bolts 3, 3. The lower section includes a conduit section 4 provided with end flanges 5, 5 by which it may be secured to adjacent units by bolts 6, 6; and, intermediate the ends, an ample uptake 7 communicating with the bottom 8 which is provided exteriorly with integral heat absorbing 45 flanges 9, 9.

The evaporator is preferably provided with a heat insulating enclosure or jacket 50 secured to flange 11 by bolts 12, and preferably formed with vent or draft outlets 13, 13 of sufficient capacity to afford the slight through draft necessary to prevent formation of a dead air pocket in the space between the upper part of the jacket and the walls of the casting.

60 The upper section of the evaporator is preferably an integral casting. The top 14 is preferably domed as shown in Figure 7 so that liquid condensing thereon will drain along the surface over to the side walls instead of dropping back into the boiling liq-

uid. The vapor conduit sections 15 are formed with end flanges 16 whereby they may be secured to adjacent units (or to a suitable closure 17) by means of bolts 18.

These vapor conduits have also the function of troughs for drainage of condensed water and for this reason the intermediate portion is carried around the circumference of the top section in the form of a gallery like, semi-tubular trough 19. This trough collects condensed water from the roof and upper walls of the evaporator and serves also as a drainage channel for similar condensation collected in and flowing from any other generator which may be coupled to it.

I have shown special means for heating the evaporator, consisting of two burners of improved construction but operating on the principle of Bunsen burners. A gas supply pipe 20 controlled by valve 21 supplies both burners through branches 23, controlled by valves 24, regulating discharge from jets 25 into a mixing chamber 26 in casting 27 supplied with air through suitable draft openings (not shown) controlled 25 by rotary dampers indicated at 28. These castings converge upwardly and are fitted within heads 27^a secured by screws 29. These heads are elongated as indicated in Figure 6 and on the upper side they are 30 formed with two parallel projecting ridges, each ridge being pierced on each side with rows of flame jet openings 30. The tips of the ridges above the jet openings are laterally widened as at 31 to overhang and protect from soot and dirt the jet openings 30 formed in the sides of said ridges. Openings 32, formed in the ends of the heads are normally closed by screw plugs 33 which may be removed for purpose of cleaning the 35 jet openings from the inside.

A branch pipe 96 having a jet 95 at the upper end may be arranged in proximity to the burner outlet as indicated in Figure 6. This affords a continuous all-gas flame 110 adapted to light the Bunsen burner jets initially or to re-light them in case they blow back or go out.

The plate 99 may be employed to serve as a partial closure for the bottom of the heating jacket.

The condenser units comprise an inner cellular structure of thin metal adapted to afford interior tortuous paths 34 extending from top to bottom thereof for flow and 120 cooling of the vapor and free drainage of the liquid condensed therefrom; and also horizontal passages 35 for flow of cooling fluid. The cellular portion is structurally rigid with and secured air tight to upper and lower terminal connections comprising metallic boxes 36 and vertically aligned entrance and exit nipples or pipes 37. Deflecting plates 38 are arranged in alignment with the interior openings or pipes 37. The end 125

boxes, pipes and deflectors are preferably in all respects similar and symmetrically arranged so that the condenser element may be inserted either end up in the casing.

6 The casing of the condenser unit preferably consists of a casing 40 conforming to but slightly larger than the condenser element. Suitable provision for receiving, circulating and discharging cooling water is 10 made, preferably by casting integral with the sides of the casing a centrally located inlet 41 aligned with a similar outlet 42, the inlet communicating with the bottom of the casing by passage 43 and the outlet being supplied from the top of the casing by passage 44. The inlet is provided with an upper flange 45 and lower bolt holes 46 and the outlet with upper bolt holes 47 and a lower flange 48 whereby the inlet may be 15 bolted to the outlet of a similar unit or the outlet to the inlet of a similar unit.

The bottom and walls of the casing are preferably integral, but the top consists of a casting 49 held in place by bolts 50 25 engaging ears 51 on the casing. The bottom and top of the casing are formed with aligned openings 52 through which the outlet and inlet pipes 37 are adapted to project. Concentric with these openings are 30 integral extensions or collars 53 enlarged interiorly as at 54 to form packing glands for a water tight packing 55 compressed and held in place by tubular extension 56 formed on the respective conduit sections, one being 35 the vapor supply conduit 58 and the other the condensed liquid conduit 59.

The annular projections 53 are formed with ears 60 and the conduit sections are formed with ears 61 through which are secured clamping bolts 62. The ends of each conduit section are provided with flanges 16 whereby they may be secured to adjacent sections by bolts 18 similar to those previously described. All these flange and bolt 40 couplings are shown as formed with intermediate annular abutment surfaces 70 adapted to be rendered steam tight by screwing them against interposed packing 71.

50 In the preferred system shown in the drawings, I interpose between the evaporator and adjacent condenser unit a special unit comprising a conduit section 73 similar to the other conduit sections preferably but not necessarily integral with an overflow device comprising stand-pipe 74 having an inlet 75, an overflow outlet 76 and an evaporator supply outlet 77. Within the stand-pipe is an upwardly projecting overflow 55 pipe 78 preferably having at its upper end a separate piece of pipe 79 screw-threaded thereto so as to permit vertical adjustment, or, unscrewing and replacing it with pipe of a different length.

56 As the outlet 77 communicates directly

with the evaporator, I prefer to arrange a transverse partition 80 indicated in dashed lines Figure 1, and in full lines Figure 8, extending a considerable distance upwards within the standpipe. This is to prevent 78 boiling water from the evaporator working back around the base of the overflow pipe 78 and finding its way upward and thus escaping through the overflow pipe. With the proportions shown and in normal 75 operation, these arrangements insure a continuous flow toward the evaporator and no backflow therefrom. There is a vent at the top of the standpipe, preferably in the form of a "breather" opening as indicated at 100, 80 Figure 1. This ensures atmospheric pressure in the standpipe and this prevents siphoning of the liquid in any direction and also serves to vent any excessive pressures arising within the system. 85

The outlet unit D has flanges 16 and clamping bolts 18 like those previously described. Intermediate the ends it is domed upwardly as at 90 and provided with an interior or upstanding wall 91 the upper edge of 90 which constitutes the overflow point from the uptake 90. 92 is a pipe for conducting away the distilled product for storage or use as may be desired. At the top of the dome 90 is a breather pipe 93, which will prevent siphoning and will also vent steam or admit air to the condensing system to prevent over pressure and vacuum conditions.

The units comprising the system may be supported in any desired way but bolt holes 101, on the evaporator units, and bolt holes 102, at the same level on the condenser units, afford a convenient means for securing them 105 between a pair of longitudinal supporting beams or channel-irons.

In operation, when the cooling water is turned on, it will flow through the several condensing units into the evaporator filling the latter to a level which is determined primarily by the height of the overflow pipe 79. After operation has been started, the liquid collecting in the discharge overflow 90 will exert a back pressure on the system sufficient to slightly lower the liquid level 110 in the evaporator as indicated in Figure 1. If this overflow 90 is empty, or if the pressure of the height of water therein is counterbalanced by the height of water in the condenser discharge pipes delivering to conduit 59, the liquid level in the evaporator will be equal to the height of the stand-pipe 79. 115

The continuously supplied cooling water after filling the evaporator will continue to flow, part of it into the evaporator to supply evaporation and the remainder through the overflow pipe 79. Pilot jet 95 will then be turned on and lit. Gas will then be turned on to the burners by valve 21 and 120 125 130

the draft intake 28 being properly adjusted, the gas will draw in a part of the air necessary for its combustion. This mixture passing out to the open air through jet openings 30 will be ignited by the pilot light. The evaporator will heat up and the water will boil. The steam passing through supply conduit B will flow through radiator inlet 37 to be deflected by plate 38, flow down through tortuous passages 34, be cooled and condensed therein and flow down through outlets 37 to conduit C. Here the condensed liquid will collect until the quantity is sufficient to overflow the outlet trap.

15 Increasing or decreasing the number of condenser units or evaporator units to suit particular uses or conditions requires only unbolting and bolting operations, which are very quickly and easily performed.

20 I prefer to maintain the evaporating and condensing system under a pressure above atmosphere because it will keep the condensers free of standing water with their entire areas operating as condensing surface. Moreover any leakage will be outward rather than inward and steam or vapor will escape to the air or to the cooling water according to the position of the leak, whereas, under vacuum conditions, any leakage 30 would be in the opposite direction and cooling water would be admitted to contaminate the distillate or air to mingle with the steam or vapor. Moreover, outward leaks of escaping steam are much more easy to detect than inward leaks of air or cooling water.

35 Whenever any unit of the system is damaged in any way, it may be easily and quickly unbolted and replaced by another unit. Or, where the radiator element only is damaged, the top section of the case of the unit may be removed, the radiator slipped out, a new radiator slipped in and the top section reapplied. In the generator unit, the burners or parts thereof may be removed 40 or cleaned or repaired without disturbing the rest of the system.

I claim:

1. A system of the class described, comprising evaporating means, an upper tubular conduit for passage of vapor therefrom, a lower tubular conduit for discharge of condensed liquid, a plurality of condensing elements connected to said conduits and communicating therewith for flow of said 50 vapor or condensed liquid downward from the upper conduit to the lower conduit in parallel relation, and a third conduit affording a path for the cooling medium to all said condensing elements in series from bottom to top in each.

2. A system of the class described, comprising evaporating means, an upper conduit for passage of vapor therefrom, a lower conduit for discharge of condensed liquid, a plurality of condensing elements

connected for flow of said vapor or condensed liquid between said conduits in parallel relation, a third conduit affording a path for the cooling medium to all said condensing elements in series and thence to the evaporator, together with an overflow standpipe in operative relation to said cooling medium for discharging liquid in excess of that necessary to replenish the evaporator before it reaches the evaporator. 75

3. A system of the class described, comprising evaporating means, an upper conduit for passage of vapor therefrom, a lower conduit for discharge of condensed liquid, a plurality of condensing elements connected for flow of said vapor or condensed liquid between said conduits in parallel relation, a third conduit affording a path for the cooling medium to all said condensing elements, said cooling medium traveling 80 away from one said conduit and toward the other along the length of each said condensing element and thence to the evaporator together with means for discharging cooling liquid in excess of that necessary to replenish the evaporator. 90

4. A system of the class described, comprising evaporating means, an upper conduit for passage of vapor therefrom, a lower conduit for discharge of condensed liquid, 95 a plurality of condensing elements connected for down flow of said vapor or condensed liquid between said conduits in parallel relation, a third conduit affording a path for the cooling medium to all said condensing elements in series from bottom to top, in each and thence to the evaporator, together with means for discharging cooling liquid in excess of that necessary to replenish the evaporator before it reaches the evaporator. 100

5. A system of the class described, comprising evaporating means, an upper conduit for passage of vapor therefrom, a lower conduit for discharge of condensed liquid, 110 an elevated overflow outlet for the latter conduit, a plurality of upright condensing elements connected for flow of said vapor or condensed liquid between said conduits in parallel relation and a conduit affording a path for the cooling medium to all said condensing elements, said lower conduit being below the upper level of the liquid in said evaporating means. 115

6. A system of the class described, comprising evaporating means, an upper conduit for passage of vapor therefrom, a lower conduit for discharge of condensed liquid, an elevated overflow outlet for the latter conduit, a plurality of upright condensing elements connected for flow of said vapor or condensed liquid between said conduits in parallel relation and a conduit affording a path for the cooling medium to all said condensing elements in series beginning 125 130

with the one nearest the outlet of said discharge conduit.

7. A system of the class described, comprising evaporating means, an upper conduit for passage of vapor therefrom, a lower conduit for discharge of condensed liquid, an elevated overflow outlet for the latter conduit, a plurality of upright condensing elements connected for flow of said vapor or condensed liquid between said conduits in parallel relation and a conduit affording a path for the cooling medium to all said condensing elements from bottom to top in each and beginning with the one nearest the outlet of said discharge conduit.

8. A system of the class described, comprising evaporating means, a conduit for passage of vapor therefrom, a conduit for discharge of condensed liquid, condensing elements connected for flow of said vapor or liquid between said conduits, a conduit for supplying a cooling medium to said condensing elements, in combination with a stand-pipe for supplying liquid to the evaporator below the surface of the liquid therein and a standpipe overflow for discharge of the condensed liquid from said discharge conduit.

9. A system of the class described, comprising evaporating means, a conduit for passage of vapor therefrom, a conduit for discharge of condensed liquid, condensing elements connected for flow of said vapor or liquid between said conduits, a conduit for supplying a cooling medium to said condensing elements, in combination with a stand-pipe for supplying liquid to the evaporator below the surface of the liquid therein and a standpipe overflow for discharge of the condensed liquid from said discharge conduit, the hydrostatic head of said discharge stand-pipe being less than the hydrostatic head of said supply stand-pipe.

10. A system of the class described, comprising evaporating means, a conduit for passage of vapor therefrom, a conduit for discharge of condensed liquid, condensing elements connected for flow of said vapor or liquid between said conduits, a conduit for supplying a cooling medium to said condensing elements, in combination with a stand-pipe for supplying liquid to the evaporator below the surface of the liquid therein and a standpipe overflow for discharge of the condensed liquid from said discharge conduit, the hydrostatic head of said discharge stand-pipe being less than the hydrostatic head of said supply stand-pipe, a connection from the outlet of the cooling liquid to the supply stand-pipe and means for adjusting the height to said overflow pipe to regulate the level of the liquid within the evaporator.

11. A system comprising evaporating means, condensing means, and separate con-

duits operatively associated therewith for the vapor supply, the cooling water supply and the condensed liquid discharge, said condensing means including a plurality of similar standard units each comprising a cellular radiator element having thin metallic walls; an exterior casing therefor each casing being formed with inlets and outlets whereby it serves as a conduit section for the cooling water; and, structurally rigid with said casing, conduit sections extending across the top and bottom thereof, the entrance and exit of said conduit sections being similarly and correspondingly arranged, and adjacent units directly coupled together to constitute the said three conduits.

12. A system comprising evaporating means, condensing means, and separate conduits operatively associated therewith for the vapor supply, the cooling water supply and the condensed liquid discharge, said condensing means including a plurality of similar standard units each comprising a cellular radiator element having thin metallic walls, affording interior vertical passages for the vapor and exterior transverse passages for passages of the cooling water; an exterior casing therefor formed with inlets and outlets whereby it serves as a conduit section for the cooling water, arranged to lead the cooling water in at the bottom and discharge it at the top of the radiator element and structurally rigid with said casing, conduit sections extending across the top and bottom thereof, the entrance and exit ends of said conduit sections being similarly and correspondingly arranged, and adjacent units directly coupled together to constitute the said three conduits.

13. A system comprising evaporating means, condensing means, and separate conduits operatively associated therewith for the vapor supply, the cooling water supply and the condensed liquid discharge, said condensing means including a plurality of similar standard units each comprising a cellular radiator element having thin metallic walls, affording interior vertical passages for the vapor and exterior transverse passages for passages of the cooling water; a casing therefor, each casing being formed with central aligned inlets and outlets whereby it serves as a section of the conduit for the cooling water arranged to lead the cooling water in at the bottom and discharge it at the top of the radiator element; and structurally rigid with said casing, conduit sections extending across the top and bottom thereof, the entrance and exit ends of said conduit sections being similarly and correspondingly arranged, and adjacent units directly coupled together to constitute the said three conduits.

14. A system comprising evaporating

- means, condensing means, and separate conduits operatively associated therewith for the vapor supply, for the cooling water supply and for the condensed liquid discharge, said 5 evaporating means including one or more similar standard units and said condensing means including a plurality of similar standard units, each condenser unit comprising a cellular radiator element having thin metallic walls and an exterior casing therefor each casing being formed with inlets and outlets whereby it serves as a conduit section for the cooling water; and, structurally rigid with each of said evaporating and condenser units, conduit sections extending across the top and bottom of each, the entrance and exit ends of said conduit sections being similarly located and correspondingly arranged, and detachably coupled together 10 to constitute the said conduits.
15. A system comprising one or more evaporator units and condenser units, said condenser units being similar and each comprising a cellular radiator element having thin metallic walls and an exterior casing therefor formed with inlets and outlets whereby it serves as a section of the conduit for the cooling water; and, structurally rigid with each of said evaporator and condenser units, conduit sections extending across the top and bottom thereof, the entrance and exit ends of said conduit sections being similarly and correspondingly arranged, and adjacent units directly coupled together to constitute separate conduits for the vapor supply, for the cooling water supply and for the condensed liquid discharge; together with an intermediate conduit between adjacent evaporator and condenser units, embodying a stand-pipe and overflow for controlling the cooling water discharged from the condenser units.
